UNITED STATES PATENT OFFICE.

ANDI CUPORAK, OF CLEVELAND, OHIO.

DESIGN FOR A SALT-BOX.

54,307.

Specification for Design.

Patented Dec. 23, 1919.

Application filed August 18, 1919. Serial No. 318,416. Term of patent 7 years.

To all whom it may concern:

Be it known that I, ANDI CUPORAK, a citizen of Czecho-Slovakia, residing at Cleveland, in the county of Cuyahoga and State of Ohio, have invented a new, original, and ornamental Design for a Salt-Box, of which the following is a specification, reference being had to the accompanying drawing, forming part thereof.

In the drawing,

Fig. 2 is a top plan view thereof.

I claim:—

The ornamental design for a salt box, as shown.

ANDI CUPORAK.
